Inventor:

Julius B. Pearlstien,
By his Attorney, Geo. W. Mealy

UNITED STATES PATENT OFFICE.

JULIUS B. PEARLSTIEN, OF BROOKLYN, NEW YORK.

SHIRT.

1,401,725.

Specification of Letters Patent. Patented Dec. 27, 1921.

Application filed August 14, 1920. Serial No. 403,493.

To all whom it may concern:

Be it known that I, JULIUS B. PEARLSTIEN, a citizen of the United States, and a resident of the borough of Brooklyn, county of 5 Kings, city and State of New York, have invented certain new and useful Improvements in Shirts, of which the following is a specification.

My improvements relate primarily to 10 shirts, although applicable to other garments of that class, the term "shirt" being herein used in its broadest sense. The object of the invention is to effectually prevent the working up and derangement of the lower part 15 of the garment during bodily motion,—the garment being particularly designed for the comfort and convenience of athletes and others addicted to vigorous physical exercise and exertion of any kind.

20 The invention consists in the specific construction and arrangement of parts described and claimed,—distinctive features being the bifurcation of the rear or tail of the garment; the peculiar convergent curvilinear 25 form of the halves of the split tail; and, in conjunction therewith, the formation of the lower front portion of the garment to cover the groin and meet and co-act with the ends 30 of the duplex tail, all as hereinafter fully set forth.

In the accompanying drawings,

Figure 1 is a front view of the shirt;

Fig. 2, is a view of the lower part thereof, indicating the function of the invention.

35 The body B, of the shirt may be of any desired form and construction, made in any manner known to the art. The tail however is split or bifurcated, the two ends t, t, thus created being convergently curvilinear, and 40 terminating in apices a, a, formed with means for attachment to the groin flaps g, g, which latter are also of convergent curvilinear shape, and are designed to extend approximately to the scrotum, the ends there- 45 of being likewise formed with means g', g', for connection with the apices a, a, of the duplex tail t, t.

The convergent curvilinear form of each tail t, t, is such that when the tail is passed 50 beneath the body crotch to one side of the scrotum, (the inner edge t', of the tail t, being of relatively slight curvature as compared with the outer edge t²) and its apex

secured to the corresponding groin flap g, the medial portion t³, of the tail will cover 55 the buttock of one leg of the wearer, as indicated in Fig. 2, thus fitting and holding the lower part of the garment snugly and tautly to the abdomen and posterior of the wearer while leaving his thighs free and un- 60 impeded for action.

Thus my form and construction of shirt enhances the comfort and convenience of the wearer while facilitating leg articulation. Furthermore, the bending or oscillation of 65 the body cannot draw up or derange the lower part of the garment, which is kept taut and in proper alinement by the attachment of the tails t, to the groin flaps g.

It is to be understood that the tails and 70 groin flaps may be disconnectably attached to each other by any suitable or known mechanical expedient, other than by means of the buttons and button holes indicated in the drawings, with like result, so that I do not 75 limit myself in this respect.

My shirt is not only suitable for general wear, but it is especially adapted to the requirements and exigencies of golf, tennis, 80 foot-ball, and other athletic games and exercises.

It is obvious that if the wearer prefers, the tails t, t, may be crossed in front and over the scrotum, etc.,—the right tail being secured to the left groin flap, and the left tail 85 to the right groin flap, so as to protect the private parts thus covered.

What I claim as my invention and desire to secure by Letters Patent is,

As an improved article of manufacture, a 90 shirt formed with a bifurcated tail the two ends thereof being convergently curvilinear and terminating in apices, the curvature of the inner edge being relatively slight as compared with that of the outer edge, groin flaps 95 of convergent curvilinear shape, the apices thereof and of said tail ends being provided with detachable fastening means, permitting the tail flaps being used either in crossed or uncrossed relation, the curvature of the groin 100 flaps and tail ends coinciding when the parts are in use.

JULIUS B. PEARLSTIEN.
